DENTAL SYRINGE

Charles C. Lake, Park Ridge, and Robert A. Grzelewski,
Buffalo Grove, Ill., assignors to American Hospital
Supply Corporation, Evanston, Ill.

Filed Feb. 9, 1970, Ser. No. 21,337

Term of patent 14 years

Int. Cl. D24—03

U.S. Cl. D24—1

FIG. 2

FIG. 3

FIG. 1

FIG. 4

FIG. 1 is a side elevational view of the dental syringe showing our new design;

FIG. 2 is a top plan view;

FIG. 3 is a rear elevational view;

FIG. 4 is a front elevational view.

The side opposite from the one illustrated in FIG. 1 is substantially identical, but the mere image of, the illustrated side.

We claim:

The ornamental design for a dental syringe, substantially as shown and described.
